GEORGE H. MORSE, OF WHEELING, WEST VIRGINIA, ASSIGNOR TO MUTUAL ELECTRIC AND MACHINE COMPANY, A CORPORATION OF WEST VIRGINIA.

MECHANICAL MOVEMENT FOR ELECTRICAL SWITCHES AND SIMILAR DEVICES.

1,169,342.

Specification of Letters Patent. Patented Jan. 25, 1916.

Application filed April 6, 1914, Serial No. 829,855. Renewed December 8, 1915. Serial No. 65,854.

To all whom it may concern:

Be it known that I, GEORGE H. MORSE, a citizen of the United States, and a resident of Wheeling, in the county of Ohio and State of West Virginia, have invented a new and useful Improvement in Mechanical Movements for Electrical Switches and Similar Devices, of which the following is a specification.

10 My invention relates to mechanical movements for electrical switches of the rotary quick-acting or snap type and for other devices of a similar nature, and it has for its object to provide a simple and economical 15 mechanical movement of this character which may be operated by turning a button or handle in either direction, if desired, and in which the parts are locked in position and are permitted to rotate only when the actuating button is turned by an operator.

20 My invention is illustrated in the accompanying drawing, Figure 1 of which is a plan view of a switch with the cover and operating button removed; Fig. 2 is a vertical sectional view through the switch on the line II—II of Fig. 1; Fig. 3 is a transverse sectional view, on the line III—III of Fig. 2, the parts being viewed from the bottom of the switch; Fig. 4 is a plan view similar to Fig. 1 but with the switch parts in the positions which they occupy just previous to their operation to effect a change in the position of the contact members; Fig. 5 is a plan view of one of the cam plates of the 30 switch, and Fig. 6 is a plan view of modified forms of cam plates that are employed when the switch is adapted for rotation in one direction only.

35 The switch comprises an insulating base 1 from the front face of which project three posts or stops 2, 3 and 4, and also three pairs of switch jaws 5, 6 and 7 that constitute the terminals of any suitable electrical system or circuit in connection with which the 45 switch is employed, the connections to the terminals being made upon the rear face of the insulating base which is recessed for the reception thereof.

50 A rotatable post or shaft 8 projects from substantially the center of the front face of the insulating base, and is provided upon its outer end with a button 9 for effecting its rotation. A substantially U-shaped arm 10 extends transversely through, and is carried 55 by, the shaft or post 8, one end of the arm

projecting between and being adapted to engage the crossed end portions of a helical spring 11 that surrounds the shaft or post 8. Also extending between the ends of the helical spring 11 is a post or stop 12 that is 60 carried by an insulating block or disk 13 that is mounted upon, but freely rotatable with respect to, the shaft 8, a bushing 14 surrounding the shaft being employed for the purpose of properly spacing the insulating block 13 from the base 1. Secured upon the rear or bottom face of the insulating block 13 is a conducting annular strip 15 having downwardly turned lips 16 that are adapted to pass between, and to engage 70 the jaws of, the terminal members 5, 6 and 7, the said lips being spaced apart sufficiently to simultaneously engage two pairs of the jaws in order to thereby electrically connect them.

75 Mounted upon the upper or front face of the insulating block 13, and retained in position thereon by means of a shoulder 19 upon the shaft 8, are two similar but oppositely or reversely arranged cam disks 20 80 and 21 which are shown more completely in Fig. 5. The cam plates are provided upon their outer edges with shoulders 22 that are adapted to engage the posts or stops 2, 3 and 4, the shoulders of the two plates 85 engaging respectively upon opposite sides of the said posts when the switch is stationary. Slots 23 are also provided in the outer peripheries of the cam plates to receive the post 12 whereby the said plates 90 are caused to rotate simultaneously with the insulating block 13 and are permitted to move transversely with respect thereto. The cam plates are also provided with central slots 24 extending in the same direction as 95 the slots 23, and the shaft 8 projects therethrough. The inside cut-away portion of each cam plate is also extended in substantially annular form, and in both directions, from one end of the slot 24 to receive the longer leg of the U-shaped arm 10, the said extensions being of different lengths and terminating in straight faces 25 and 26 that are not in alinement but are substantially 100 parallel, and are adapted to be engaged by the end of the arm 10 for the purpose of effecting transverse movements of the plates. By reason of the fact that the faces 25 and 26 are not in alinement, they are engaged 105 in succession by the arm 10 when the button 110

9 is turned, and, consequently, the cam plates are moved in succession so as to disengage the shoulders 22 from the posts 2, 3 and 4, the first plate to be moved being that, the 5 shoulder of which is upon the front side of the post with respect to the direction of rotation. The cut-away portions of the plates are also so shaped as to provide faces 27 that engage the arm 10 when the said 10 plates are rotated following the movement of the said arm, the plates being thereby moved transversely and in succession so that the shoulders 22 thereon will engage that one of the posts 2, 3 and 4 toward which 15 the switch is rotated for the purpose of thereby stopping the movement of the switch and of locking it in position, the last plate retracted being the first to make the return movement.

20 In the operation of the switch, the button 9 may be turned in either direction, and, when this is done, the spring 11 is subjected to strain, thereby applying resilient pressure upon the post 12 tending to rotate the insulating block 13 and the parts carried thereby. When the button 9 has been rotated through an angle of substantially 90 degrees, the longer end of the arm 10 engages the face 25 of one of the cam plates 20 and 21, and, upon continued rotation of the button, the arm 10 first causes the shoulder 22 of one of the cam plates to disengage that one of the posts 2-3-4 with which it was previously in engagement, and, upon 30 still further rotation, the arm 10 engages the face 26 of the other cam plate and, in turn, causes the shoulder 22 upon the said cam plate to disengage the stationary post. Insulating block 13 is then driven forward by the strain of the spring 11, and the faces 27 of the cam plates successively engage the longer end of the arm 10 and the plates are moved outwardly in succession to cause the shoulders 22 thereon to engage the next stationary post. The movement of the switch parts is thereby stopped, and the switch is again locked in position so that it cannot be moved except by rotation of the button 9.

50 In Fig. 6, a modification of the cam plates is shown which modification is employed when it is desired to provide for rotation of the switch in one direction only. In this case the annular cut-away portions of the plates are only about half as long as in the preceding figures, that in one plate being similar in shape to one end of the cut-away portion of the plates of the preceding figures and that in the other plate being similar to the other end thereof.

55 60 While the present invention is shown as applied to an electrical switch, it is to be understood that it may be employed wherever its functions may be advantageously utilized without departing from the spirit and scope of the invention.

I claim as my invention:

1. A mechanical movement comprising a plurality of stationary stops, a manually rotatable member provided with an arm, a driven member provided with a post, resilient means interposed between the arm and said post upon the driven member that is subjected to strain when the manually rotatable member is rotated, and similar oppositely arranged cam plates rotatable with the driven member and having opposing shoulders upon their outer edges adapted to engage the stationary stops upon opposite sides thereof and faces adapted to be engaged by the arm carried by the manual rotatable member whereby the shoulders upon said plates are disengaged from the stationary stops and are caused to reengage them upon rotation of the driven member. 70 75 80

2. A mechanical movement comprising a plurality of stationary stops, a manually rotatable member provided with an arm, a driven member, resilient means interposed between the said members that is subjected to strain when the manually rotatable member is rotated, and cam plates rotatable with the driven member and having opposing shoulders adapted to engage the stationary stops upon opposite sides thereof and faces adapted to be engaged by the arm carried by the manually rotatable member whereby the shoulders upon said plates are disengaged from the stationary stops and are caused to reengage them upon the rotation of the driven member. 85 90 95 100

3. A mechanical movement comprising a plurality of stationary stops, a manually rotatable member provided with an arm, a driven member, resilient means interposed between the said members that is subjected to strain when the manually rotatable member is rotated in either direction, and cam plates rotatable with the driven member and having opposing shoulders adapted to engage the stationary stops upon opposite sides thereof and faces adapted to be engaged by the arm carried by the manually rotatable member whereby the shoulders upon said plates are disengaged from the stationary stops and are caused to reengage them upon the rotation of the driven member. 105 110 115

4. A mechanical movement comprising a plurality of stationary stops, a manually rotatable member provided with an arm, a driven member, resilient means interposed between the said members that is subjected to strain when the manually rotatable member is rotated, and cam plates rotatable with the driven member and having opposing shoulders adapted to engage the stationary stops upon opposite sides thereof, faces adapted to be engaged in succession by the arm carried by the manually rotatable member to cause the said shoulders to disengage the said stops, and cam faces also adapted 120 125 130

- to be engaged by the said arm whereby the said shoulders are caused to reengage the said stops upon rotation of the driven member.
- 5 5. A mechanical movement comprising a plurality of stationary stops, a manually rotatable member provided with an arm, a driven member, resilient means interposed between the said members that is subjected to strain when the manually rotatable member is rotated, and cam plates rotatable with the driven member and having opposing shoulders adapted to engage the stationary stops upon opposite sides thereof and faces adapted to be engaged by the arm carried by the manually rotatable member whereby the shoulders upon the said plates are disengaged in succession from the stationary stops and are caused to reengage them in succession and in the reverse order upon rotation of the driven member.
- 15 15. A mechanical movement comprising a plurality of stationary stops, a manually rotatable member provided with an arm, a driven member, resilient means interposed between the said members that is subjected to strain when the manually rotatable member is rotated, and cam plates rotatable with the driven member and having opposing shoulders adapted to engage the stationary stops upon opposite sides thereof and faces adapted to be engaged by the arm carried by the manually rotatable member whereby the shoulders upon the said plates are disengaged in succession from the stationary stops and are caused to reengage them upon rotation of the driven member.
- 20 6. A mechanical movement comprising a plurality of stationary stops, a manually rotatable member provided with an arm, a driven member, resilient means interposed between the said members that is subjected to strain when the manually rotatable member is rotated, and cam plates rotatable with the driven member and having opposing

shoulders adapted to engage the stationary stops upon opposite sides thereof and faces adapted to be engaged by the arm carried by the manually rotatable member whereby the shoulders upon the said plates are disengaged in succession from the stationary stops and are caused to reengage them in succession and in the reverse order upon rotation of the driven member.

7. A mechanical movement comprising a rotatable supporting member, a pair of superposed cam plates carried by said member and movable transversely thereof, an actuating member for the cam plates, means whereby the actuating member may apply a torque to the supporting member, and means co-operating with the cam plates to stop the movements of the supporting member and to lock it in predetermined positions.

In testimony whereof I have hereunto subscribed my name this 31st day of March, 1914.

GEORGE H. MORSE.
